UNITED STATES PATENT OFFICE.

JAMES L. NEVILLE, OF O'FALLON, MISSOURI.

STUMP-EXTRACTOR.

SPECIFICATION forming part of Letters Patent No. 244,648, dated July 19, 1881.

Application filed September 28, 1880. (Model.)

To all whom it may concern:

Be it known that I, JAMES L. NEVILLE, a citizen of the United States, residing at O'Fallon, in the county of St. Charles and State of Missouri, have invented an Improvement in 5 Stump-Extractors, of which the following is a specification.

The object of my invention is to simplify the construction and to increase the efficiency 10 and power of those stump-extractors in which a capstan, sweep, and carrier are employed.

My improvement consists, first, in a stump-extractor provided with a capstan moved vertically and adapted to be raised by the elevating ropes or chains which are built upon 15 themselves between the head and bearing-plate in winding them around the capstan, and adapted to be lowered by unwinding the said ropes or chains, as hereinafter described.

My improvement consists, secondly, in a bearing-plate having inclines or cams adapted to direct the ropes or chains over each other as they pass up through the beam to the capstan, as hereinafter described.

My improvement consists, thirdly, in a 20 stump-extractor provided with an evener or carrier having sheaves or pulleys at each end, in combination with sheaves or pulleys working within the beam, and suitable ropes or 25 chains passing around the sheaves or pulleys and connected with the capstan, as hereinafter described.

In order that my invention may be fully understood, I will proceed to describe it with 30 reference to the accompanying drawings, in which—

Figure 1 is a perspective view of my improved stump-extractor, the capstan and carrier being in their lower position. Fig. 2 is a 35 perspective view of the capstan and its adjacent parts, showing the ropes or chains built upon themselves and the capstan and carrier elevated thereby. Fig. 3 is a vertical longitudinal section thereof. Fig. 4 is a top view 40 of the same.

F may represent a suitable frame forming a 45 substantial support to a beam, B, and may be mounted on wheels W. The beam is provided with a bearing-plate, D, having inclines or cams I, and through which the cap-

stan C is permitted to move vertically. S is the sweep secured to the upper end of the capstan and suitably braced thereto.

E is an evener or carrier, which consists of two plates or bars secured together by bolts 55 furnished with suitable grappling hooks or chains, H, at its center and provided with a link or clevis, L, and pulley or sheave P² at each end. These sheaves are mounted on the 60 bolts.

The beam B is excavated so as to form a vertical slot, within which are mounted lower sheaves or pulleys, P' P', or upper sheaves or 65 pulleys, P³ P³, in such position as to permit the lower end of the capstan to pass down between them centrally of the beam.

R R are two ropes or chains, each secured at one end to a link, L, on the evener, then passed over a sheave, P', above, within the beam, then under a sheave, P², beneath, in the 70 evener, then passed over a sheave, P³, above, in the beam, and the other end secured beneath the head K of the capstan. Each sheave P³ is set obliquely to the beam, so as to bring the outer side in line with the outer side of 75 the lowest sheave, P², and its inner side in line with the periphery of the capstan, so as to direct, when the sweep and capstan are turned, the rope or chain in front of the vertical wall of an incline, I, beneath the under 80 coil and onto an incline. The ropes or chains are thus built up between the head K of the capstan and the inclines, which elevates the carrier E and capstan at the same time. The evener or carrier is adapted to equalize the 85 weight brought to bear on the capstan.

By my construction it will be seen that great power and efficiency in working are obtained, while the whole machine is of most simple construction.

Having thus described my invention, the following is what I claim as new therein and desire to secure by Letters Patent—

1. The combination of the sliding capstan, 90 rope, and sweep, the capstan adapted to be elevated by building up the coils of rope, as explained.

2. The combination of the sliding capstan C, having head K, ropes R R, inclines I I, and a suitable sweep, as set forth.

90

100

3. The combination of bearing-plate D, having inclines I I, oblique sheaves P³ P³, ropes R R, and sweep S, as set forth.

4. The combination of upper sheaves, P³ P³, 5 lowersheaves, P² P², within the beam B, evener E, having sheaves P' P', capstan C, ropes R R, and a suitable sweep, S, as set forth.

5. The combination of the evener E, having sheaves P' P', and links L L, ropes R R, capstan C, and sweep S, as set forth.

JAMES L. NEVILLE.
